UNITED STATES PATENT OFFICE.

JOHN MUELLER, OF ST. LOUIS, MISSOURI.

ARCH-SUPPORT.

1,289,515

Specification of Letters Patent. Patented Dec. 31, 1918.

Application filed September 19, 1918. Serial No. 254,772.

To all whom it may concern.

Be it known that I, JOHN MUELLER, a citizen of the United States, residing at St. Louis, State of Missouri, have invented certain new and useful Improvements in Arch-Supports, of which the following is a full, clear, and exact description, reference being had to the accompanying drawings, forming a part hereof.

10 The present invention is directed to improvements in arch-supports, and has for its object to provide a support adapted to be secured to the insole of the shoe in the regions of the heel and ball of the foot, the 15 support being so formed as to permit the introduction of inserts at points where the break or weak point in the arch is most pronounced, special provision being made for holding an insert against the inside arch of 20 the foot in the form of a pocket or insert receptacle, such pocket being independent of the means for holding an insert against the bottom arch of the foot. The present support may be fitted to any of the standard 25 makes of shoes, there being no change necessary in the construction of the shoe proper. The support is sufficient in extent to supplement the usual insole as a support for the foot, and possesses advantages which will be 30 fully apparent from the following detailed description of the invention in connection with the accompanying drawings in which—

Figure 1 represents a side elevation of a shoe partly in longitudinal middle vertical section to expose the layers of the support and of the outsole and insole of the shoe; Fig. 2 is a vertical cross-section on the line 2—2 of Fig. 1; Fig. 3 is a similar section showing an insert leading from the side 40 pocket of the support across the arch; Fig. 4 is a bottom plan of the insole and support with parts of the insole broken away to expose the layers of the support, the layers being broken away in the region of the shoe 45 shank to expose an insert disposed across the bottom of the arch; Fig. 5 is a side elevation of the arch-support shown in Fig. 4 turned one-hundred and eighty degrees to the right, one-half of the insole being in middle longitudinal section; and Figs. 6 and 7 are plans of two examples of inserts.

Referring to the drawings, S represents a conventional shoe, the same being provided with the usual outsole 1, insole 2, shank 55 brace 3, filler 4 and welt 5 as well under-

stood in the art. In the present embodiment of my invention I form the arch-support of a bottom resilient layer or member 6 of metal or equivalent material, over which is superposed an upper flexible layer 7 of 60 leather or like material, the leather layer preferably overlapping the layer 6 in the region of the ball of the foot, the two layers being secured to the insole in the region of the heel by a rivet 8, and the overlapping end 65 of the layer 7 being secured to the insole by stitches 9 in the region of the ball of the foot at which point the support terminates, the two layers being loose from one another except at the rivet 8 to permit of the introduction between them of suitable inserts as presently to appear. The layers 6 and 7 cover the insole from the heel to the ball of the foot, spanning the full length and width of the shank of the shoe, and on the inside they 70 curve upwardly to engage the inside arch of the foot as clearly appears from Figs. 1, 2, and 3, the support as a whole thereby engaging both the bottom and inside arches. Sewed or otherwise secured to the free convexed edge of the upturned portion of the leather layer 7 which by the way slightly overlaps the corresponding upturned portion of the layer 6, is a flap 10 which is otherwise 75 loose from the layer 7 thereby leaving a 80 pocket a between the flap and layer 6, for the introduction of one end of an insert as presently to be seen.

The layers 6 and 7 being riveted to the insole at the heel, but loose from one another otherwise, permit of the ready introduction between them, along the length of the shank of the shoe and hence along the length of the arch of the foot, of suitable inserts such as 11, an example of which is 95 shown in Figs. 4 and 6, where the length of the insert is sufficient to extend entirely across the bottom and inside arches of the foot. In the illustration Fig. 4, the insert 11 is shown approximately opposite the middle of the shank of the shoe, but it is apparent that it may be shifted or adjusted anywhere along the support between the rivet 8 and the opposite ends of the layers 6 and 7. Again, in Fig. 3 is shown an insert 12 with 105 its curved end (Fig. 7) inserted into the pocket a behind the flap 10, and then brought between the insole 2 and bottom metal layer 6 of the arch-support. The flap 10 of course prevents the insert 12 from rubbing against 110

the upper of the shoe and thus assists in preventing the insert from displacement once it has been deposited opposite the inside arch of the foot. The shapes and lengths of the 5 inserts as shown in Figs. 6 and 7 are merely by way of example and I may resort to an insert of any required shape according to the degree of support desired and depending too on the location of the weakest point of the 10 arch to be supported.

One of the main advantages of the present construction lies in the fact that an insert may be introduced between the layers 6 and 7 and adjusted to any position along 15 the arch between the heel and ball of the foot; and that a special insert may be placed opposite the inside arch of the foot, said insert being maintained against longitudinal displacement and prevented from rubbing 20 against the shoe upper by the flap 10 which forms a pocket (a) for receiving the upper end of the insert. The stitching of the leather layer 7 to the insole is not absolutely necessary but is desirable. In Figs. 2 25 and 3 the cross-section of the shoe upper is shown more or less diagrammatically, hatching being omitted to better bring out the features immediately involved in the invention. The construction of the support is 30 obviously susceptible of more or less modification without involving a departure from the nature or spirit of the invention.

Having described my invention what I claim is:

35 1. An arch-support comprising a bottom resilient member spanning the shank of the shoe longitudinally and laterally and extending from the region of the heel to the ball of the foot, and arched to conform to 40 the bottom and inside arches of the foot, an upper yielding layer conforming to the bottom layer but loose therefrom to permit the introduction of an insert between the layers, and a third member comprising a 45 sheet or flap spanning the inside arch of the first member and having a curved upper edge secured to the corresponding curved edge of the inside arch of the second member, the first and third members being loose 50 from one another to form a pocket for the

introduction of an insert between them for supporting the arch of the foot.

2. In combination with a shoe insole, an arch-support comprising a bottom resilient layer spanning the bottom and inside arches 55 of the foot longitudinally and laterally, a flexible layer deposited loosely on top of the bottom layer and conforming thereto in curvature and being substantially the same in extent, means for securing said layers to 60 the insole in the region of the heel, means for securing the upper layer to the insole in the region of the ball of the foot, said layers being adapted to receive between them an insert to support the arch of the foot, and 65 a third layer or flap secured to the second layer along the curved edge of the turned-up portion thereof opposite the inside arch of the foot, said third layer being loose from the first layer to permit of the introduction 70 of an insert affording support to said inside arch.

3. In combination with a shoe insole, an arch-support comprising a bottom resilient sheet metal member spanning the length 75 and width of the shank of the shoe and conforming to the arched formations of the foot, an upper flexible sheet member conforming to the dimensions and contour of the bottom member, and loose therefrom to 80 allow for the introduction of an insert between the members, the members being secured to the insole in the region of the heel, and the upper member being stitched to the insole at points adjacent the ball of the foot, 85 and a flap secured at one edge to the curved free edge of the turned-up portion of the upper member opposite the inside arch of the foot and loose from the sheet metal member to permit of the introduction between 90 said member and flap of a suitable insert, the parts operating substantially as and for the purpose set forth.

In testimony whereof I affix my signature, in presence of two witnesses.

JOHN MUELLER.
